UNITED STATES PATENT OFFICE.

SAMUEL J. LARGE, OF BRISTOL, CONNECTICUT, ASSIGNOR TO THE BRISTOL
BRASS AND CLOCK COMPANY, OF SAME PLACE.

DESIGN FOR A SPOON OR FORK HANDLE.

SPECIFICATION forming part of Design No. 31,428, dated August 22, 1899.

Application filed July 26, 1899. Serial No. 725,201. Term of patent 3½ years.

To all whom it may concern:

Be it known that I, SAMUEL J. LARGE, a citizen of the United States, residing in Bristol, in the county of Hartford and State of Connecticut, have invented and produced a new and original Design for a Spoon or Fork Handle, of which the following is a specification, reference being had to the accompanying drawings, in which—

10 Figure 1 is a face or plan view of a spoon or fork handle, showing my design. Fig. 2 is a view of the reverse side of the same.

The design being for the handle alone, the spoon-bowl is indicated in broken lines.

15 The opposite side edges of the handle at its smaller end are concave, as at 3, 4, and 5, with points 6 and 7 at the junction of said concavities and convex portions 8 on the broader part of the handle, with a central three-lobed 20 or trefoil figure 9 at the upper end. There is a border-bead 10 following the greater por-

tion of the edge on the front side, with an inner bead 11 substantially parallel thereto, and with scroll leaflets 12 between the points 6 and 7 and at the upper end of the handle, together with a central leaflet 17 opposite the trefoil 9, the said leaflets being mainly between the border-beads. The reverse side of the handle is also provided with the outer and inner border-beads 13 and 14, with leaflets 15 inside 3 of the inner bead between the points 6 and 7, while a semirosette 16 is opposite the trefoil 9, all as shown.

Having described my invention, what I claim as new, and desire to secure by Letter Patent, is—

The design for a spoon or fork handle as herein shown and described.

SAMUEL J. LARGE.
